8920

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 14,478, dated December 11, 1883.

Application filed October 27, 1883. Term of patent 3½ years.

To all whom it may concern:

Be it known that I, CATHERINE O'HARA, of the city, county, and State of New York, have invented and produced a new and original Design for a Pattern of a Girl's Costume, (numbered 8,920;) and I do hereby declare that the engraved prints accompanying this specification convey to any one accustomed to using paper patterns a clear understanding of how a garment made up by the pattern will appear.

The design combines a walking-skirt with an overdress. The latter has vest-fronts buttoned for part of their depth and rounded away below the closing, deeper side fronts that overlap the vest-fronts to within a few inches of the closing, and are draped by plaits in their

back edges, and a half-fitting back that is amplified by extra widths at the ends of its body-seams, and draped by a cluster of plaits at its center, and deep single plaits in its side edges. 20 coat-sleeves, a standing collar, and a deep cape-collar being added.

What I claim as my invention, and desire to secure by Letters Patent, is—

The design for a girl's costume, as shown in 25 the engraved prints accompanying this specification.

CATHERINE O'HARA.
